UNITED STATES PATENT OFFICE.

ROBERT WILLIAM DAVIS, JR., OF ASPINWALL, PENNSYLVANIA.

ELECTRIC HEATING UNIT AND METHOD OF MANUFACTURING THE SAME.

1,211,102.

Specification of Letters Patent. Patented Jan. 2, 1917.

Application filed August 26, 1912. Serial No. 717,042.

To all whom it may concern:

Be it known that I, ROBERT WILLIAM DAVIS, Jr., a resident of Aspinwall, Allegheny county, Pennsylvania, have invented 5 a new and useful Electric Heating Unit and Method of Manufacturing the Same, of which the following is a full, clear, and exact description, reference being had to the accompanying drawings, forming part 10 of this specification, in which—

Figure 1 is a perspective view of one form of improved heater made in accordance with my invention; and Fig. 2 is a sectional view through one form of mold, 15 containing one form of heater.

This invention relates to an improvement in electric heating units, and the method of making the same.

The object of the invention is to provide 20 a device of this character which will be simple and efficient, and which can be cheaply and readily manufactured from cheap raw materials, which may readily be obtained.

25 The precise nature of my invention will be best understood by reference to the accompanying drawings, which will now be described, it being premised, however, that various changes may be made in the details 30 of construction and general arrangement of the parts, without departing from the spirit and scope of my invention as defined in the appended claims.

In the drawings, the numeral 2 designates 35 the body of the unit, and 3 the supporting legs in the form shown in the drawings.

40 4 are lead wires extending to the ends of the resistance wire 5, which is partially embedded in the body 2. This resistance is provided with a plurality of parallel members connected to each other in series by downwardly extending loops, the upper faces thereof being approximately flush with the upper face of the body, while 45 the loops are embedded in the body of the material to retain the resistance in position with relation thereto.

The body 2 preferably consists of asbestos and cement, which are mixed in suitable 50 proportions, for example, about one pound of asbestos to seven pounds of cement, which are thoroughly mixed with water to form a plastic mass.

In the preferred method of manufacturing, I utilize a mold, such as shown in section at 6 in Fig. 5, together with a presser

plate 7. I first place the wire or bars, which are formed of resistance material, in the mold, and permit the ends to extend therefrom for attaching the leads. I then 60 place sufficient of the plastic mass into the mold and tamp it around the wires, and then place the presser 7 in position and press the material by any well known method, or I may compress it by means of 65 screws 8 extending through lugs 9 on the presser plate, and which engage screw-threaded orifices in lugs 10 extending from the mold. After the mass has been pressed to a predetermined degree, it is allowed to 70 remain under pressure in the mold for about twelve to fifteen hours to permit the slab to set. The slab may then be removed from the mold and an electric current may be intermittently passed through the resist- 75

ance for a short time so as not to overload the lead wires, until after the water has been driven out of the slab. In this way the slab may be dried in a few minutes and 80 may be immediately used to heat any suitable object or material.

It will be readily understood by those familiar with the art that the slab may be increased in any suitable manner so that any portion or the entire unit may be covered 85 to meet the particular requirements for which the unit is to be used. It will also be understood that the unit may be reinforced in any desired manner to provide a unit which has sufficient strength to re- 90 sist the various stresses and strains to which it would be subjected when in use. It will readily be understood by those familiar with the art that any form of terminal or switch may be used which may be connected to the 95 unit or detached therefrom; also that insulating tablets or shields may be used in conjunction therewith to protect table tops and the like. These insulating members may be connected to the unit in any desired manner 100 or may be detached therefrom.

The advantages of my invention result from the provision of a heat unit which can readily be manufactured, and in which the resistance wires are embedded in a body of 105 asbestos and cement.

I claim:—

1. An electric heating unit consisting of a molded body formed of asbestos and cement together with electric resistance material 110 said resistance material having a plurality of exposed members on the upper surface of

the body, and a plurality of loop members embedded in the body connecting said exposed members in series with each other; substantially as described.

5 2. An electric heating unit, consisting of a molded body portion formed of asbestos and cement and electric resistance material, said body portion having legs formed integrally therewith, the resistance material having a plurality of parallel members on the upper surface of the body and downwardly extending loop members embedded in the body, said loop members connecting the parallel members in series with each other; substantially as described.

10 3. The method of manufacturing hard, elastic and smooth faced electric heating units, which consists in placing resistance material in the mold, then placing a plastic mass of asbestos mixed with water and cement in the mold over the resistance material, then applying pressure to the mold to compress the plastic mass therein, and retaining the mass under pressure a sufficient 20 time to permit the mass to change its chemical nature by absorbing chemically hydrous water, substantially as described.

25 4. The method of manufacturing electric heating units, which consists in first placing the electric resistance material in a mold, then placing a plastic mass of asbestos and cement in the mold around the wire, then compressing the plastic mass within the mold, and permitting the article to remain 30 in the mold until set, and then drying the

mass by intermittently passing an electric current through the resistance material; substantially as described.

5. An electric heating unit consisting of a body portion having legs integral therewith, an electric resistance material having a plurality of members at the surface of the body, and a plurality of loop members connected to said members and embedded in the body arranged to anchor the resistance material thereto; substantially as described.

40 6. An electric heating unit comprising a body portion of asbestos and cement, in combination with a plurality of resistance members at the surface of the body, said resistance members having loops connected thereto and embedded in the body to anchor the resistance members thereto, said body portion being hard and elastic and having smooth surfaces and sharp edges; substantially as described.

45 7. An electric heating unit comprising a body having integral legs formed of asbestos and cement, a plurality of resistance members at the surfaces of the body, and a plurality of loops connected to said resistance members and embedded in the body, said body portion and legs being hard and elastic and having smooth surfaces.

50 In testimony whereof, I have hereunto set my hand.
